UNITED STATES PATENT OFFICE.

FREDRICK N. BRENNER, OF TELL CITY, INDIANA.

BAND-SAW GUIDE AND GUARD.

Application filed December 8, 1921. Serial No. 520,975.

To all whom it may concern:

Be it known that I, FREDRICK N. BRENNER, a citizen of the United States, residing at Tell City, in the county of Perry and State 5 of Indiana, have invented certain new and useful Improvements in a Band-Saw Guide and Guard, of which the following is a specification.

This invention relates to band-saw guides 10 and guards, and more specifically to an improved device combining a band-saw guide and guard.

One object of this invention is to provide a device of this character which perfectly 15 guides the cutting portion of a band-saw while cushioning the same for permitting a limited and yieldingly resisting rearward movement of this cutting portion.

A further object is to provide a device of 20 this character which eliminates or greatly reduces friction between the saw and the guide.

A further object is to provide a device of 25 this character whose guiding elements are individually adjustable and provided with individual lubricating means.

A further object is to provide a device of 30 this character whose connection with its support is capable of an infinite number of adjustments both vertically and horizontally.

A further object is to provide a device of 35 this character which is adjustable to fit band-saws of different thicknesses, also to provide new wearing parts on the saw-back-guide when grooves have worn therein.

Other objects and advantages will be pointed out or implied in the following details of description, in connection with the accompanying drawings, in which:

40 Fig. 1 is a front elevation of my improved band-saw guide and guard.

Fig. 2 is a side elevation thereof.

Fig. 3 is a vertical sectional view, the sections being taken on different planes.

45 Fig. 4 is a rear view with a portion broken away to show certain interior features.

Fig. 5 is a vertical sectional view along the line 5—5 of Fig. 1.

Fig. 6 is a vertical sectional view along the line 6—6 of Fig. 1.

Fig. 7 is a horizontal sectional view along the line 7—7 of Fig. 1, one of the guide-rollers being shown in full lines.

50 Fig. 8 is a view showing the guard-plate in horizontal section, and showing the main body or casing in top plan.

Fig. 9 is a detail plan view illustrating one of the rollers which constitutes an element of the saw-back-guide, also the supporting axle and plungers for this roller. 60

Referring to these drawings in detail, in which similar reference characters correspond with similar parts throughout the several views, and in which the saw is indicated in broken lines at S, for showing the application of the device, the invention consists in the construction, arrangement and adjustable relation of parts, as will now be fully described in the following:

Referring to Figs. 1 and 2 of the drawings, it will be seen that the main body 1 is provided with a front cover 2, the latter being formed of two plates which are spaced from one another, as indicated at 3, to provide a passage which registers with a slot 4 70 in the upper side or top of the body or hollow casing 1. The plates 2 are provided with upwardly extending portions 5 between which the teeth of the saw travel, so that these plates form a guard to prevent an operator or other person from coming into contact with the saw-teeth which are thus guarded; it being understood that the saw travels in the passage provided by the openings 3 and 4, also through an opening 6 in 75 the bottom of the casing 1.

Upper and lower pairs of saw guides or rollers 7 and 8 are mounted in the casing 1, preferably on ball bearings, as indicated in Fig. 7 including balls 9, cones 10, a screw-threaded shaft 11 for each of these rollers, and lock-nuts 12 for each roller. One shaft 11 of each pair is provided with an eccentric journal portion 13, these shafts being journaled in bearings 14 which are formed 80 in the rear part of the casing 1, and are rotatable in these bearings for bringing these rollers 7 and 8 of each pair in the proper spaced relation for fitting saws of different thicknesses, it being understood that the saw S travels between the rollers of each pair while passing through the passages 85 3—4 and 6. Set screws 15 are provided for securing the shafts 11 in adjusted position.

The saw-back-guide preferably comprises 90 a pair of rollers 16 which are preferably mounted on ball-bearings 9—10—17—12, as illustrated in Fig. 3. The screw-threaded shaft 17 of each roller 16 is preferably slotted at 18 to provide seats against which set-screws 19 are seated for holding these shafts 17 in different longitudinal adjust- 95 100 105 110

ments while preventing them from rotating. By adjusting these shafts longitudinally, new portions of the rollers 16 can be brought into the saw-guiding position when a groove has been worn by the saw in another part of the saw-back-guide. These rollers or saw-back-guides 16 are preferably mounted, through the medium of their shafts 17, in radial openings 20 through two pairs of plungers 21, these plungers being mounted in sockets 22 and pressed forward by means of springs 23, respectively, and each socket 22 is mounted for longitudinal adjustment in an opening 24 in the back of the casing 1. Each socket 22 is preferably slabbed at 25 for engaging with a set-screw 26 for holding these sockets, respectively, in different longitudinal adjustments while preventing rotation thereof. The object of longitudinally adjusting the elements 16, 21 and 22 is to compensate for saws of different widths.

The casing 1 is preferably supported by an eccentric shaft 27 which has one end portion fitted in an opening or bearing 28 in the central rear portion of the casing 1, the casing also being provided with a boss 30 into which is fitted a set screw 31 which bears upon the shaft 27 and holds it against accidental rotation or longitudinal movement. The outer end portion of the shaft 27 is preferably engaged with a depending support 32 which is provided with a set-screw 33 for holding the members 27 and 32 against accidental movement with respect to one another. By loosening the set-screws 31 and 33, then turning the shaft 27, the casing 1 and the parts carried thereby are freed for adjustment both vertically and horizontally. By adjusting the device vertically with respect to the saw, more or less cutting surface of the saw is exposed or made available between this device and the saw-table T. By adjusting the device laterally of the saw, the latter can be properly located between the rollers 7 and 8 so as to prevent undue lateral pressure of the saw against any one or two of these rollers. By adjusting the casing 1 forward or rearward, and appropriately adjusting the saw-back-guide, in the manner previously described, the saw can be held in proper relation to the pulleys (not shown) while the saw-teeth are properly guarded by the plates 2.

Referring again to Fig. 7, and especially to the eccentric 13 whereby the adjustment of one of the rollers 7 and 8 of each pair

is obtained, it is noted that the front nut 12 is circular and fits in a circular opening 34 of each plate 2. Therefore, in order to obtain this lateral adjustment of the rollers 7 and 8, either the openings 34 must be sufficiently large to permit of such adjustment, or the bolts 35 pass through openings 36 (in the plates 2) of sufficient size to permit one or both of the plates 2 to move with the outer nuts 12 when these bolts 35 are loosened.

For the purpose of properly lubricating the ball-bearings of the rollers 7, 8 and 16, their shafts 11 and 17 are preferably provided with ducts 37, through which lubricating grease can be forced by means of grease-cups 39 of any appropriate or well known kind. These grease-cups have their outlets registering with the ducts 37, and by screwing up the covers of the grease-cups, grease is forced through these ducts to the interior of the guiding rollers so that the ball-bearings may be kept properly lubricated. The grease-cups of the shafts 17 also constitute knobs whereby these shafts can be adjusted longitudinally.

Although I have shown the set-screws 15, 31 and 19 as socket-screws, that is, provided with sockets to fit a socket-wrench, any appropriate form of screw or securing means may be employed for holding the several parts in adjustment. Moreover, it is not intended to limit this invention to the exact details of construction and arrangement here described and shown, but changes may be made within the scope of the inventive ideas as implied and claimed.

What I claim as my invention is:

In a saw guiding device, the combination of upper and lower pairs of rollers, the rollers of each pair being spaced for receiving and guiding a saw therebetween, a saw-back-guide mounted between the upper and lower pairs of rollers, this saw-back-guide comprising a roller having its axis at right angles to a plane coinciding with the spaces between the rollers of the upper and lower pairs, and means for supporting the saw-back-guide and for adjusting the same so as to bring different parts thereof in position to contact with the back of the saw when the latter is traveling in the space between the rollers of said pairs, said means being spring pressed in the forward direction for yieldingly resisting backward movement of the saw.

In testimony whereof, I affix my signature.

FREDRICK N. BRENNER.
